US00D714717S

(12) **United States Design Patent**
Nakanoue et al.

(10) **Patent No.:** US D714,717 S
(45) **Date of Patent:** ** Oct. 7, 2014

(54) **REACTOR**

(71) Applicant: **Hitachi Industrial Equipment Systems Co., Ltd.**, Tokyo (JP)

(72) Inventors: **Kenji Nakanoue**, Tokyo (JP); **Naoyuki Kurita**, Tokyo (JP)

(73) Assignee: **Hitachi Industrial Equipment Systems Co., Ltd.**, Tokyo (JP)

(**) Term: **14 Years**

(21) Appl. No.: **29/480,830**

(22) Filed: **Jan. 30, 2014**

(30) **Foreign Application Priority Data**

Aug. 26, 2013 (JP) 2013-019501

(51) **LOC (10) Cl.** 13-02

(52) **U.S. Cl.**

USPC **D13/101**

(58) **Field of Classification Search**

USPC D13/101, 133, 184, 199; 356/432, 436, 356/437; 422/28, 37, 129, 139, 140, 141, 422/145, 236; 423/477, 478; 376/220, 228, 376/230, 347; 336/90, 178, 184, 210, 211, 336/212, 213, 219
